UNITED STATES PATENT OFFICE.

WILLIAM F. BOSSERT, OF UTICA, NEW YORK, ASSIGNOR TO SIGNAL ACCESSORIES CORPORATION, OF UTICA, NEW YORK, A CORPORATION OF NEW YORK.

PIPE CARRIER.

Application filed July 2, 1924. Serial No. 723,712.

This invention relates to a new and improved pipe carrier. The main object of the invention is to produce a simple, efficient pipe carrier of rigid and substantial construction capable of easy and rapid assemblage, and of such adjustment as is desirable in connection with such devices.

A further object resides in the production of a base constituting a portion of the pipe carrier that is adapted for use with either concrete or iron piers of usual construction.

Other objects and advantages relate to the details of the construction and form of the device as will more fully appear from the following description taken in connection with the accompanying drawings in which:

Figure 1 is a top plan view of a pipe carrier of my invention.

Figure 2 is a section on line 2--2, Figure 1.
Figure 3 is a perspective view of the base of Figures 1 and 2.

Figures 4 and 5 are perspective views of modified forms of bases.

The structure as shown in Figure 1 illustrates a unit of the pipe carrier of my invention and comprises two bases —1— of similar form and shape and each comprising a substantially flat body portion —2— formed with elongated openings or slots —3— at the opposite sides of each base and with an elongated opening or slot —4— at substantially the central portion of each base.

A description of one of these bases will constitute a description of both and each base is in the form of an integral casting as illustrated.

At one side of the base, there is provided a pair of spaced upright complementary clamping members —5— and —6—, each clamping member terminating near its upper portion in an arcuate or somewhat semi-circular pipe clamping part, between which clamping members, a pipe or rail —7— is adapted to be passed so that when the bolt —8— is passed through the spaced lower portions of the clamping members —5— and —6—, and the nut —9— is threaded on the bolt, the arcuate upper portions —10— and —11— will tightly grip the pipe —7— and hold it rigidly in place with respect to the base —1—.

At the opposite side of the base —1—, there is provided a similar pair of upright spaced clamping members —12— and —13— terminating at their upper portions likewise,

in arcuate or substantially semi-circular pipe clamping parts —14— and —15— through which the pipe or side rail —16— is adapted to be passed and about which the arcuate parts —14— and —15— are tightly clamped when the bolt —17— is passed through the spaced lower portions of the spaced upright clamping members —12— and —13— and the nut —18— is threaded on the bolt.

In the construction illustrated in Figures 1 and 2, the bases —1— are secured to a concrete pier —19— by means of opposite disposed hook bolts —20— having their hook portions extending into recesses in the pier and their upper portions extending through the respective slots —3— and equipped with nuts —21— for tightly clamping the base to the pier.

The usual form of pipe carrier may be utilized in connection with the structure so far described, and as shown, these pipe carriers are formed with legs terminating in opposite feet —22— adapted to rest upon the pipes or rails —7— and —16— respectively, and to be secured thereto by hook bolts —23— having their hook portions extending around the respective pipes —7— and their upper portions extending through openings in the feet —22— of the pipe carriers proper, and equipped with nuts —24— for tightly clamping the feet —22— to the pipes —7— and —16— respectively.

In the usual manner, rollers —25— are carried by each two adjacent pipe carrier supports —26— and upon these rollers the pipes —27— are carried.

In Figure 3, the base of Figures 1 and 2 is independently illustrated and due to the provision of the opposite slots —3— for use in connection with concrete piers and the central elongated opening or slot —4— adapted for use in connection with iron piers, the pipe carrier support of this invention is adapted for use in connection with either construction of pier.

In Figure 4, I have illustrated a base adapted for use only in connection with concrete piers as illustrated in Figure 2 in that it is provided only with the slots —3— and omits the slots —4— whereas in Figure 5, I have illustrated a base adapted for use only in connection with iron piers in that it is formed with the slot —4— but omits the opposite edge slots —3—.

In all of these constructions, however, the

integral spaced upright clamping members with complementary arcuate clamping parts or jaws at their upper ends are provided.

Although I have shown and described a specific construction and form of parts, as illustrative of an embodiment of my invention, I do not desire to restrict myself to the exact form, shape or arrangement of the parts, as various changes may be made within the scope of the appended claim.

I claim:

A pipe carrier comprising a body portion provided with an elongated slot through which a bolt is adapted to extend for ad-

justably securing the carrier to a support, and upright pairs of complementary pipe clamping members integral with the base, each member having an arcuate upper portion so that each pair is adapted to receive a pipe, the upright members of each pair being spaced apart throughout substantially their entire length, and means disposed below the arcuate portions for drawing the uprights of each pair toward each other to tightly grip a pipe.

In witness whereof I have hereunto set my hand this 25th day of June, 1924.

WILLIAM F. BOSSERT.
